United States Patent Office

Des. 195,894
Patented Aug. 6, 1963

195,894

SUNGLASS FRAME OR THE LIKE

Albert C. Petitto, Hudson, and Vitalino Marchi, Concord, Mass., assignors to Foster Grant Co., Inc., Leominster, Mass., a corporation of Delaware

Filed Dec. 15, 1961, Ser. No. 67,918

Term of patent 14 years

(Cl. D57—1)

FIG. 1

The side not shown is substantially like the side shown. The rear is substantially plain and conventional.

We claim:

The ornamental design for a sunglasses frame or the like, substantially as shown and described.
